UNITED STATES PATENT OFFICE.

JOHN H. SCHOREGGE AND THEODORE SCHOREGGE, OF SIOUX FALLS,
SOUTH DAKOTA.

WASHING-MACHINE.

No. 825,939.

Specification of Letters Patent.

Patented July 17, 1906.

Application filed April 20, 1905. Serial No. 256,686.

To all whom it may concern:

Be it known that we, JOHN H. SCHOREGGE and THEODORE SCHOREGGE, citizens of the United States, residing at Sioux Falls, in the county of Minnehaha and State of South Dakota, have invented certain new and useful Improvements in Washing-Machines; and we do hereby declare the following to be a full, clear, and exact description of the same, reference being had to the accompanying drawings, forming a part of this specification, and to the letters of reference marked thereon.

This invention relates to improvements in washing-machines, and particularly to that class known as "pounder-machines," in which the clothes are agitated and the water driven through them by means of reciprocating devices.

The invention consists in certain novel details of construction and combinations and arrangements of parts, all as will be now described, and the particular features of novelty pointed out in the appended claims.

In the accompanying drawings, wherein is illustrated the preferred embodiment of the present invention, Figure 1 is a view in elevation of the machine with the tub or clothes-receptacle broken away. Fig. 2 is a section on the line *x* *x*, Fig. 1. Fig. 3 is a detail view of one of the pounders.

Similar letters of reference in the several figures indicate the same parts.

Referring to the drawings, the letter *A* indicates a tub or clothes-receptacle of substantially cylindrical shape and preferably formed of metal, such as galvanized iron. This receptacle is suitably mounted upon legs or supports *a*.

On the outside of the tub *A*, near its top, is secured a bracket *a'*, in which is journaled a short shaft *a''*, carrying at one end a sprocket-wheel *a'''* and at its other end a drive-wheel *a''''*, provided with a handle *a'''''*, by means of which it may be turned. Passing over the sprocket-wheel *a'''* is a sprocket-chain *a''''*, said chain passing over a second sprocket-wheel *a''''*, carried by a shaft *a''''* beneath the tub, journaled in brackets *a'''' a'''''*, secured to the tub *A*, all as shown in Fig. 1. At the inner end of shaft *a''''* is secured a crank-arm *b*, connected, by means of a pin *b'*, with one end of a link *b''*, passing through an opening *b''* in the bottom of the tub *A*, preferably near the center, the

other end of the link being connected to a reciprocating rod *b''''*.

It will be noted that the crank-arm is counterweighted in the present instance by the integral enlargement shown at *b''''*. Over the opening *b''* in the bottom of the tub *A* is fitted a casing or envelop *c*, of suitable metal, secured to the bottom by suitable fastening means, as rivets *c'*, passing through the base-flange *c''*. This envelop *c* is substantially cone shape, as shown, thus affording room for the movements of the link *b''* within the envelop, as will be understood, the link being thus kept from contact with the water in the tub.

In order to protect the reciprocating rod *b''''* from the water, an enveloping casing consisting of a tube *c''* is provided, mounted on the top of the casing *c*, within which the rod *b''''* works. Surrounding the tube *c''* is a collar *c''''*, having a tubular extension *c''''*, closed at the upper end, the rod *b''''* and inclosing tube *c''* passing up into the extension *c''''*, and the rod *b''''* is formed with a reduced screw-threaded end *b''''''*, which passes through the end of the extension *c''''* and receives a nut *b'''''''*. The arrangement is such that while the extension and rod are secured together the extension is permitted to turn about the rod for a purpose to be presently explained. The collar *c''''* is also provided with a downwardly-extending tubular extension *c''''''*, which fits over the tube *c''*, from which construction it results that the collar will be guided by three extensions on the tube *c''* in its up-and-down movement and will not be liable to tip and bind on the tube. Secured to the collar *c''''* at diametrically opposite points thereof are the arms *d d'*, and upon the outer ends of these arms are secured T-shaped couplings *d''*. Working in the heads of these couplings are the rods *d''*, which carry at their lower ends the pounders *e e'*, the upper ends of the rods *d''* being headed, as shown at *d''''*, to prevent them from falling entirely through the couplings *d''*.

In machines of this class it is very desirable that in addition to their reciprocating or up-and-down movement the pounders should also have a revolving motion around the tub in order that all the portions of the clothes should be acted on. In the present instance this motion of the pounders is accomplished by the peculiar shape of the pounders.

Referring particularly to Fig. 3, it will be

seen that the pounders have a front or advance face e' substantially parallel with the line of reciprocation of the pounders and a rear or follow face e^2 inclined to said line of reciprocation. By this construction little or no resistance will be offered by the water upon the front face of the pounders as they are lifted up through the water, whereas considerable force will be exerted by the water upon the rear or follow face, tending to push or impel the pounders forward, whereby the pounders will be caused to be revolved about the tub, as will be readily understood.

In order that the pounders may yield when brought in contact with the clothes, a spring e^6 is interposed between the couplings d' and top of the pounders e .

The operation of the machine will now be understood. When the hand-wheel is turned, the rod b^3 , through the described connections, will be caused to reciprocate, thus reciprocating the pounders, which by their peculiar construction will be caused to revolve around the tub.

25 The machine is simple, easily operated, and the various working parts are perfectly protected from the water.

Having thus described our invention, what we claim as new, and desire to secure by Letters Patent, is—

30 1. In a washing-machine, the combination with the water-receptacle, of a reciprocating rod, the arms rotatably mounted thereon, the couplings secured to the ends of the arms, the headed rods working through said couplings, the pounders carried by said rods, driving mechanism operatively connected to the reciprocating rod through an opening in the bottom of the receptacle, a cover for said 35 opening and a casing for the reciprocating rod carried by said cover; substantially as described.

40 2. In a washing-machine, the combination with the tub, of a reciprocating rod, driving

mechanism, operatively connected to said 45 rod through an opening in the bottom of the tub, a cover for said opening, a casing for said rod, a rotatable collar supported by said casing, the arms carried by said collar, the pounders connected to said arms, so formed 50 as to cause said arms to be rotated when the pounders are drawn up through the water.

3. In a washing-machine, the combination with the central reciprocating rod, a casing therefor, a collar pivotally mounted on said rod having upper and lower tubular extensions surrounding the casing, the arms carried by said collar and the pounders carried by said arms, and mechanism for reciprocating the rod; substantially as described. 55

4. In a washing-machine, the combination with the reciprocating rod, of the arms rotatably mounted thereon, the pounders carried by said arms, said pounders having a front face substantially parallel with the line of reciprocation of the pounders and a rear face inclined thereto, whereby as the pounders are lifted through the water, an impelling force will be exerted upon said rear face and the pounders caused to rotate about the tub; 60 substantially as described.

5. In a washing-machine, the combination with the pounders, of a rotatable and reciprocatory carrier for said pounders said pounders having a front face substantially parallel 75 with the line of reciprocation of the pounders and a rear face inclined thereto, whereby as the pounders are lifted through the water an impelling force will be exerted on said rear face of the pounders and the pounders caused 80 to rotate about the tub; substantially as described.

JOHN H. SCHOREGGE.
